[57] CLAIM

The ornamental design for a combined gameboard,

game pieces, and container therefor, as shown and described.

DESCRIPTION

FIG. 1 is an exploded perspective view of the combined gameboard, game pieces, and container therefor embodying my new design;

FIG. 2 is an exploded perspective view thereof as disassembled from play;

FIG. 3 is a side view in elevation thereof as assembled for play;

FIG. 4 is an end view thereof prior to assembly for play;

FIG. 5 is a top plan view thereof prior to play; the game pegs have been omitted for clarity of illustration

FIG. 6 is a perspective view thereof as fully assembled for transport;

FIG. 7 is a top plan view thereof as fully assembled for transport;

FIG. 8 is a side view in elevation thereof as fully assembled for transport;

FIG. 9 is an end view in elevation thereof as fully assembled for transport;

FIG. 10 is a bottom plan view thereof as fully assembled for transport.
